Samuel Boyd, of New York, N.Y.
Letters Patent No. 1216 dated April 3, 1860

The schedule referred to in these Letters Patent and making part of the same.

To all whom it may concern:

Be it known that I, Samuel Boyd, of the City, County & State of New York, have invented and produced a new and original design for Andirons, and I hereby declare, that the following is a full and exact description thereof, illustrated by the drawings which accompany and form a part of these my specifications.

It consists of a Female Figure in alto relief dropped in the Antique Grecian Style and seated on a rock - her left hand is resting on her breast, and her right grasps the Scroll of a Lyre at her side, the pedestal of which Lyre, rests on the rock at her feet - at her left foot springs seedly foliage extending upward nearly to her knee.

Beneath the rocky base, and from its center springs plumage & scroll-work, which terminates in scroll feet on each side of the figure - These feet form the front legs of the Andiron - The bar for holding wood and the back foot is to cast separately and fits with a dovetail into a slot cast in the hollow reverse of the figure, and when placed in position forms an Andiron of elegant and classical appearance.

What I claim and desire to secure by Letters Patent, is the above described Design for Andirons, made as, set forth and illustrated in its general configuration and component parts.
